ALEXANDER GIRTANNER, OF ST. LOUIS, MISSOURI.

PACKING-RING FOR PISTONS.

1,111,063.

Specification of Letters Patent. Patented Sept. 22, 1914.

Application filed February 19, 1914. Serial No. 819,649.

To all who... may concern:

Be it known that I, ALEXANDER GIRTANNER, a citizen of the United States of America, residing at the city of St. Louis, State of Missouri, have invented a certain new and useful Packing-Ring for Pistons, of which the following is such a full, clear, and exact description as will enable any one skilled in the art to which it appertains to make and use the same, reference being had to the accompanying drawings, forming part of this specification.

My invention relates to packing rings for pistons, and has for its object the production of a packing ring which will not be liable to allow the passage of steam or gases between the ring and the piston when the ring is in position.

In the accompanying drawings, which illustrate a packing ring made in accordance with my invention, Figure 1 is a sectional view of a cylinder and piston, showing a pair of my rings in position; Fig. 2 is a top plan view of one of the rings; Fig. 3 is a side view of one of the rings, one end of one of the parts being broken away; Fig. 4 is a side view of one part of one of the rings, and Fig. 5 is a side view of the other part of the ring.

Like marks of reference refer to similar parts in the several views of the drawings. 10 represents a piston arranged in a cylinder 11. The piston 10 is provided with the usual rectangular annular grooves 12, in the present instance, two in number. In each of these grooves is arranged one of the piston rings. Each of the piston rings consists of a part 13 and a part 14, the co-acting faces of which are beveled, as best shown in Fig. 1. Each of the parts 13 and 14 of the ring is divided by a slot in the usual manner. The main object of my invention is to so arrange these slots that they cannot be brought into alinement to allow the passage of the motor fluid. I, therefore provide the part 13 with an inclined slot 15 extending in one direction, and the part

14 with an inclined slot 16 extending in the opposite direction, as shown in Fig. 2. As shown in Fig. 2, the two parts of the ring 50 are arranged so as to bring the two slots 15 and 16 as nearly as possible in alinement. In this position, however, the projecting point 17 on the part 13 and the projecting point 18 on the part 14 will overlap through 55 the entire depth of the ring, as best shown in Fig. 3, so that even in the most unfavorable position, the slots will be almost entirely closed. It will be understood, however, that in placing the rings in position, 60 the two parts should be arranged so that the slots will be entirely out of alinement. In case, however, the slots should work around to the position shown in Fig. 2, a very slight leakage of the motor fluid will be allowed. 65

It has been customary heretofore to prevent the slots in the two parts of a packing ring being brought into alinement by means of a pin set into one of the parts and engaging with a recess in the other part. By 70 my construction, however, I so form the slots that their relative position is practically immaterial, and, I, therefore, obviate the use of the pin and thus avoid the weakening of the ring which is consequent on 75 such construction.

Having fully described my invention, what I claim as new and desire to secure by Letters-Patent of the United States is:

The combination with a piston provided 80 with an annular groove, of a packing ring composed of two parts placed side by side in said groove, each of said parts being divided by an inclined slot to produce overlapping points, the co-acting points of the 85 two parts extending in opposite directions.

In testimony whereof, I have hereunto set my hand and affixed my seal in the presence of the two subscribing witnesses.

ALEX. GIRTANNER. [L. S.]
